The ornamental design for a rear panel for utility vehicle, as shown and described.

DESCRIPTION

The present invention relates to a rear panel for a utility vehicle, particularly a golf cart.

FIG. 1 is a perspective view of the panel of the present invention;

FIG. 2 is a front view of the panel of the present invention; FIG. 3 is a rearward view of the panel of the present invention;

FIG. 4 is a top view of the panel of the present invention; FIG. 5 is a bottom view of the panel of the present invention; and,

FIG. 6 is a perspective view of the panel of the present invention on a golf cart.

The panel has a curved contour and extends from the side of the cart towards the rear of the cart when installed. A window is provided for visibility.
